(57) **CLAIM**

The ornamental design for a chair, as shown and described.

DESCRIPTION

FIG. 1 is a front perspective view of a first embodiment of the chair embodying the new design;

FIG. 2 is a side view thereof;

FIG. 3 is a front view thereof;

FIG. 4 is a rear view thereof;

FIG. 5 is a top view thereof;

FIG. 6 is a bottom view thereof;

FIG. 7 is a front perspective view of a second embodiment of the chair embodying the new design;

FIG. 8 is a side view thereof;

FIG. 9 is a front view thereof;

FIG. 10 is a rear view thereof;

FIG. 11 is top view thereof; and,

FIG. 12 is a bottom view thereof.

FIGS. 1-12 show portions of the chair in broken lines. The portions shown in broken lines are for environmental purposes only and form no part of the claimed design. Stipple shading is added to convey surface contouring; the stipple shading is not to be understood as conveying a particular surface finish.
